UNITED STATES PATENT OFFICE.

HENRY HOWARTH, OF DETROIT, MICHIGAN, ASSIGNOR TO THE HOWARTH REVERSIBLE SASH AND SASH CENTER COMPANY, OF SAME PLACE.

TRANSOM-PIVOT.

SPECIFICATION forming part of Letters Patent No. 499,923, dated June 20, 1893.

Application filed November 14, 1892. Serial No. 451,933. (No model.)

To all whom it may concern:

Be it known that I, HENRY HOWARTH, a citizen of the United States, residing at Detroit, in the county of Wayne and State of Michigan, have invented certain new and useful Improvements in Window-Sash Centers, of which the following is a specification, reference being had therein to the accompanying drawings.

10 This invention consists in the peculiar construction of a center especially adapted for hanging heavy sashes from the sides and so constructed that one man alone can hang the sash, and further whereby a simple and strong 15 construction is obtained with a dust and sight-proof joint, all as more fully hereinafter described.

In the drawings, Figure 1 is a perspective view of the parts of my sash center detached. 20 Fig. 2 is a vertical, central section through my sash center showing it as applied in use. Fig. 3 is an elevation of a window frame illustrating the manner of applying my center.

25 A is a plate, preferably circular. Centrally upon one side of this plate is formed a gradually enlarging pin or stud B. The upper face C of the plate around the pin is inclined upward from the edge toward the pin, and the 30 upper face D of the pin or stud is convex, or substantially conical. The plate A around the pin is provided with suitable apertures E by means of which it may be secured to the sash. This forms the pivot member of my 35 sash center. The socket member thereof is composed of two complementary plates F F', each of which has formed on its inner edge a semicircular flange G, the inner face H of which is inclined inward toward its base and 40 the plate within the flange is concave, as shown at I, the top of the flange J inclining inwardly.

K are securing apertures formed in the plate, outside the flange.

L is a securing aperture in one of the halves 45 within the flange.

The parts being thus constructed the operator finds the center line on the frame and secures thereto the two lower halves F' of the center at opposite sides, countersinking the 50 plates flush with the face of the frame. He then secures the pivoted base of the center to the sash, preferably countersinking them, as shown in Fig. 2, and then engages the pins into the half sockets already secured in position, and the frame will rest therein and the operator may turn it to its horizontal position, as shown in Fig. 3 and insert the upper 55 half of the socket, securing them by means of suitable screws M, when the device will be 60 complete. The upper half is more readily secured by beveling the upper edge of the plate F, as shown at N.

The inclined face C, the inclined upper face of the cone D and the inclined face N on the 65 plate all aid in inserting the upper plate after the lower plate is in position and the sash is hung from the pivots.

What I claim as my invention is—

A sash center consisting of a pivot member 70 having a pivot pin thereon formed with sides inclining outwardly from a point adjacent to the base, and a socket member having its inner walls of a contour substantially that of the pin head, and divided centrally into two 75 sections each provided at one side only with outwardly extending perforated plates, substantially as described.

In testimony whereof I affix my signature in presence of two witnesses.

HENRY HOWARTH.
